CLAIM

The ornamental design for an abdominal exercise machine, as shown and described herein.

DESCRIPTION

FIG. 1 is a perspective view of our abdominal exercise machine;

FIG. 2 is a front elevation view thereof;

FIG. 3 is a rear elevation view thereof;

FIG. 4 is a right side elevation view thereof;

FIG. 5 a top plan view thereof;

FIG. 6 is a bottom view thereof; and,

FIG. 7 is a perspective view thereof, in an alternate position. The broken line portions of the disclosure are for illustrative purposes only and form no part of the claimed design.
